UNITED STATES PATENT OFFICE.

EDWARD W. BURT, OF BROOKLINE, MASSACHUSETTS.

THERAPEUTIC SHOE.

9,84,506.

Specification of Letters Patent. Patented Feb. 14, 1911.

Application filed May 3, 1910. Serial No. 553,126.

To all whom it may concern:

Be it known that I, EDWARD W. BURT, a citizen of the United States, residing at Brookline, in the county of Norfolk and State of Massachusetts, have invented new and useful Improvements in Therapeutic Shoes, of which the following is a specification.

My invention relates to improvements in therapeutic boots and shoes and its object is to construct a shoe which will dispense with the use of mechanical appliances or artificial supports and at the same time develop and strengthen the muscles of the foot.

In so-called "flat-foot", plates of steel or other material are made, which serve as mechanical braces, and support the arch of the foot and neutralize the tendency to pronation. Such a construction has been found to be inefficient, not only giving no cure but at best furnishing only temporary relief. A tilted or twisted plate does not tilt or twist the foot, but on account of its arbitrary fixity only makes the foot try continuously to get away from it, and causes considerable pain. Plates and stiff shoes are made because of the belief that the foot has a fixed arch, whereas the truth is, that the foot has the power of arching. The corrective mechanical arch does not restore the natural arch of the foot but only holds up the bones like a crutch.

There are distinct traces of grasping movements, which may be, and often are, cultivated by barefooted races, and by individuals who are armless or have lost the control of their hands. This grasping power which depends largely on the strength and mobility of the great toe is lost in shoe-wearing people. After all, the principal uses of the foot are to serve as a base of support for the body and to assist in the propulsion of the body in walking. The foot as a base is not inert, but elastic and adjustable, and assists in balancing the body; this is a very important and little noticed use of the foot. When the feet are weak, deformed or improperly shod, the posture, balance and efficiency of the whole body suffer. The strong, movable, great toe is a great help in balancing the body of the shoeless primitive man; shoe-

wearing people have lost this help from the confinement and weakness of the great toe. The strength of the foot is such that it is more elastic and yielding on its inner (arched) side. When the foot is weakened or strained it tends to turn and roll outward, while the ankle falls inward, making the ankle bone prominent. This tendency is opposed by the muscles, which turn and roll the foot inward, shifting the weight to the outer border of the foot, where it should fall. The outward roll is also opposed in barefooted people by the pressure of the great toe directed somewhat inwardly; this protection is entirely lost in shoe-wearing people, and the development of the protecting muscles is much interfered with.

No normal foot is ever sharply pointed in the middle as are so many shoes. It is longest (and nearly straight) on the inner side; and the end of the shoe which ought never to be sharply pointed, should lie over the normal position of the great toe; that is, toward the inner side. The great toe is never normally pushed outwardly toward the other toes; this is the effect of improper footwear.

My invention is designed to permit the muscles of the foot to act in their normal relations as above described and to this end I have constructed a shoe, which while rigid in the parts exposed to wear and external injury is at the same time made flexible at the point where the natural foot is flexible and permits the great toe and muscles thereof to act in the manner of the natural aboriginal foot without shoes.

My invention essentially consists in constructing a shoe in which the arch of the sole is made of great flexibility, the uppers above said arch and adjacent part of the shoe being also of considerable flexibility to coöperate with the flexibility of said arch of the sole.

Attention is hereby made to the drawings in which similar numerals of designation refer to similar parts throughout the several views.

Figure 1. is a side elevation of one of my improved shoes, the shoe designed for the right foot being illustrated. Fig. 2. is a

vertical longitudinal section of the shoe illustrated in Fig. 1. Fig. 3. is a view of the shoe shown in Fig. 1, looking at the same from below. Fig. 4. is a view of the shoe 5 showing the great flexibility of its shank.

Referring to the drawing, the shoe there shown is composed of the outer sole, 5, the inner sole (5'), the heel 6, and upper, 7. The outer sole 5, is constructed in two thicknesses, one thickness of which 8, is located directly underneath the toes and ball of the foot of the wearer and is the wearing surface coming in contact with the ground, and the other thickness 9, being directly underneath the instep or arch of the foot and extending below the heel thereof. Preferably the part 9, is made one half the thickness of the part 8, but since the thickness of said part is really measured by the amount of 20 flexibility required at the arch 10, of the outer sole 5, the thickness of the sole at the arch 10, may be varied provided that said sole may without difficulty be easily bent at this point. In forming the said sole I find 25 it essential therefore, that the leather of the sole 5, be skived or otherwise reduced in thickness at the region of said arch, but I do not find it necessary to reduce the thickness of said sole at any other part though I have 30 in the preferred form illustrated in drawing shown the thickness of the sole reduced under the heel of the wearer as well as under the instep. But since the heel of the shoe adds to the thickness of the part 9, it will be 35 seen that such reduction is only apparent and that practically the thickness of the part 9 is not really reduced at this point. Below the part 9 at the extremity thereof and extending forward, I secure to said part 40 in the well known manner the heel 6, which has embodied therein at the outer front corner the soft rubber cushion 11, constructed with a flange 12 for securing the same between the layers of said heel and with depressions 13 for affording a gripping surface to come in contact with the ground. I prefer to locate the said cushion at this 45 point for the purpose of avoiding a pivot for the heel to swing on and to throw the 50 toes of the foot inwardly and thereby insure proper and correct contact with the surface walked upon.

The inner sole 5', is made of soft flexible leather or other suitable material, and the 55 same is preferably slashed laterally with a knife to render it still more pliable. The heel portion 14, of the upper 7, is formed with the vamp seam 16, located just to the rear of the arch 10, and is given the proper 60 rigidity by use of the usual stiffening 15. The said vamp seam 16 is so located because otherwise if the same were farther forward, it would interfere with the required flexure 65 of the sole 5, and further that more freedom

is given to the action of the tarsal bones and 65 muscles allowing the foot to roll outwardly, free and unhampered. It will also be observed that the toe of the shoe upper is constructed upon broad lines conforming to the shape of the foot, and permits the outward 70 sweep of the toes and the raising of the dorsum of the foot as the toes grasp the sole.

While I have described my invention with particular reference to its use for a foot the arch of the instep of which is flattened so 75 that the entire sole thereof rests upon the ground, I by no means desire to be limited to such restricted use, since it is obvious that my shoe can be worn to advantage by normal persons and so prevent the evils the shoe 80 is designed to cure.

What I claim and desire to secure by Letters Patent is,

1. A shoe of the character described comprising an upper provided with a broad toe 85 and low counter, and conforming to the natural shape of the human foot, a sole secured to said upper and provided with a flexible arch, and a low heel secured to said upper and provided at its outer forward corner with pivoting means acting to swing the toes of the foot inward, and co-operating with the flexible arch to free the tarsal bones and muscles from restraint, whereby the weight of the body is shifted involuntarily 95 to the outer border of the foot.

2. A shoe of the character described comprising an upper provided with a broad toe and low counter and conforming to the natural shape of the human foot, a sole secured to said upper and provided with a flexible arch, and a low heel also secured to said upper and provided at its outer forward corner with a section of frictional material 100 acting to swing the toes of the foot inwardly, 105 and co-operating with the flexible arch to free the tarsal bones and muscles from restraint, whereby the weight of the body is shifted involuntarily to the outer border of the foot.

3. A shoe of the character described comprising an upper provided with a broad toe and low counter, and conforming to the natural shape of the human foot, a sole secured to said upper and provided with a flexible arch, and a low heel secured to said upper and provided at its forward corner with a recess, and a rubber cushion fitting within said recess and having a flange secured between the lifts of said heel, said 115 cushion acting to swing the toes of the foot inward, and co-operating with the flexible arch to free the tarsal bones and muscles from restraint, whereby the weight of the body is shifted involuntarily to the outer 120 border of the foot.

4. A shoe of the character described comprising an upper provided with a broad toe

and low counter, and conforming to the natural shape of the human foot, a sole secured to said upper and provided with a flexible arch, and a low heel secured to said upper; the forward outer corner of said heel being constructed to swing the toes of the foot inward, and coöperating with the flexible arch to free the tarsal bones and muscles from restraint, whereby the weight of the

body is shifted involuntarily to the outer border of the foot.

In testimony wherof I have hereunto set my hand in presence of two subscribing witnesses, this 29th day of April 1910.

EDWARD W. BURT.
